CLAIM

The ornamental design for charm for eyeglasses, as shown and described.

DESCRIPTION

FIG. 1 is a front elevational view of a charm for eyeglasses showing my new design;

FIG. 2 is a back elevational view thereof;

FIG. 3 is a right side elevational view thereof;

FIG. 4 is a left side elevational view thereof;

FIG. 5 is a top elevational view thereof;

FIG. 6 is a bottom elevational view thereof;

FIG. 7 is an isometric back view thereof; and,

FIG. 8 is an isometric in use of the device attached to the temple of a pair of eyeglasses with a silicone band. The broken lines depict portions of the environment that

form no part of the claimed design.

1 Claim, 4 Drawing Sheets
